CLOTHESLINE CLEANER

Thomas Esposito, South Orange, N. J., assignor of
one-half to John W. Fiore, Orange, N. J.

Application February 27, 1940, Serial No. 321,115

1 Claim. (Cl. 15—246)

This invention relates to cleaners for clothes lines and similar devices, and has for the primary object the provision of a device of this character which may be installed on the mounting of a clothes line with the latter extending therethrough so that prior to hanging clothes or other articles on the line, said line may be caused to pass through the device throughout its length for efficiently removing dirt and other foreign matter therefrom, obviating any possibility of the clothes hung on the line becoming dirty or soiled by having direct contact with said line.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating an endless clothes line equipped with a cleaner constructed in accordance with my invention.

Figure 2 is a vertical sectional view illustrating one of the parts of the cleaner which is adapted to apply water or other cleaning fluid to the clothes line.

Figure 3 is a transverse sectional view taken on the line 3—3 of Figure 2.

Figure 4 is a view similar to Figure 3 showing the liquid applying device spread or opened to permit the insertion or removal of the clothes line therefrom.

Figure 5 is a vertical sectional view illustrating another part of the present invention and employed for drying the line.

Figure 6 is a sectional view taken on the line 6—6 of Figure 5.

Referring in detail to the drawing, the numeral 5 indicates a clothes line of the endless type supported by pulleys 6. The pulleys are journaled in mountings 7 of a conventional construction and which may be attached to supporting posts 8 in a well known manner. The before described parts merely briefly set forth an endless type clothes line and its mountings for the purpose of illustrating the application of the present invention to such a device. It is to be understood that the invention may be used on clothes lines other than the endless type.

A liquid applying device 9 receives one of the runs of the clothes line as clearly shown in Figure 1 of the drawing while the other run of the clothes line passes through a drying device 10.

The cleaning and drying devices 9 and 10 are provided with brackets 11 engageable with one

of the mountings 7 and retained thereon by set screws 12. The brackets 11 secured to the mountings as shown in Figure 1 of the drawing will prevent the liquid applying device and the drying device from moving with the clothes line when the latter is caused to travel over the pulleys.

The liquid applying device consists of a tubular shaped metallic casing 13 in which is located a core 14 constructed of spongy rubber or other suitable material. The core 14 has a bore 15 extending from end to end thereof and through which the upper run of the clothes line passes. The metallic casing 13 as well as the core are slit longitudinally from end to end and the slit of the core communicates with the bore 15 thereof. The slits of the casing and core align so that the casing may be flexed open as well as the core to permit the easy insertion of the clothes line into the bore of the core. The metallic casing is provided with a series of perforations or openings 16 so that water or other cleaning fluid may be supplied to the core for absorption thereby. It is to be understood that the cleaning device 9 may be removed from the mounting and submerged into water or other liquid whenever it is desired to give the device a thorough cleaning. After the application of the cleaning device on the clothes line a movement of the latter through the bore of the core will thoroughly saturate the clothes line with water or other fluid for softening and otherwise aiding in the loosening of foreign material which may be adhering to the clothes line. The movement of the clothes line as specified also travels through the drying device 10 for removing the foreign matter along with the water or moisture placing the line in a clean condition for the hanging of clothes and other articles thereon without danger of soiling.

The cleaning device 10 includes a metallic casing 17 constructed similarly to the casing 13 except for the openings or perforations. Located in the casing 17 is a core 18 having a bore 19 through which the line extends or the lower run thereof, as clearly shown in Figure 1. The core 18 is also slit to align with the slit in the casing 17 to permit the easy and quick application of the lower run of the line into the bore of the core 18.

In actual use the core 18 made of felt is an extremely efficient core for the drying of the clothes line. However, other absorbing materials may be employed if desired. Further, it is to be understood that the metallic casings are capable of being flexed so as to permit opening of the

cores confined therein for the application and removal of the line.

A device of this kind is easily applicable to a clothes line and its mounting and will efficiently remove dirt and other foreign matter from the line placing the latter in proper condition for the support of clothing and like articles without the danger of soiling the latter. Furthermore, it will be seen that the device can be manufactured and sold at a comparatively low cost.

It is believed that the foregoing description, when taken in connection with the drawing, will fully set forth the construction and advantages of this invention to those skilled in the art to

which such a device relates, so that further detailed description will not be required.

Having thus described my invention, what I claim is:

5 In a device of the character described, a metallic tubular shaped casing, a core in said casing and having a bore to receive a clothes line, said core being of a liquid absorbing and applying material, said casing having a plurality of openings 10 to admit liquid to the core thereof, a bracket carried by said casing for detachably mounting the latter onto a support of a clothes line.

THOMAS ESPOSITO.
